DESIGN FOR A RUPTURE PAD

Al H. Hoffman, Azusa, Calif.

Application March 13, 1943, Serial No. 109,749

Term of patent 14 years

To all whom it may concern:

Be it known that I, Al H. Hoffman, a citizen of the United States, residing at Azusa, in the county of Los Angeles and State of California, have invented a new, original, and ornamental Design for a Rupture Pad, of which the following is a specification, reference being had to the accompanying drawing, forming part thereof.

Figure 1 is a front elevational view of a rupture pad showing my new design.

Figure 2 is an inside elevational view thereof.
Figure 3 is a side elevational view.

Figure 4 is a section on the line 4—4 of Figure 1.

I claim:

The ornamental design for a rupture pad, as shown.

AL H. HOFFMAN.
